UNITED STATES PATENT OFFICE

94,618

DESIGN FOR A BOTTLE

Russell J. Miedel, Oakland, Calif., assignor to Hazel-Atlas Glass Company, Wheeling, W. Va., a corporation of West Virginia

Application December 14, 1934, Serial No. 54,424

Term of patent 14 years

To all whom it may concern:

Be it known that I, Russell J. Miedel, a citizen of the United States, residing at Oakland, in the county of Alameda, and State of California, have invented a new, original, and ornamental Design for a Bottle, of which the following is a specification, reference being had to the accompanying drawing, forming part thereof.

The figure is a perspective view of the bottle showing my new design.

The side of the bottle opposite to that shown is preferably plain.

I claim:

The ornamental design for a bottle as shown and described.

RUSSELL J. MIEDEL.
